(57) **CLAIM**

The ornamental design for a card reader for mobile communicator, as shown and described.

DESCRIPTION

FIG. 1 is a top perspective view of the card reader;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

In the drawings, both broken lines and broken & dotted lines are used. The broken lines in the drawings illustrate the unclaimed environment of the design, and form no part thereof. The broken & dotted lines in FIGS. 1 and 3 illustrate the bounds of the claimed design and form no part thereof.
